FIG. 1.

FIG. 2.

FIG. 3.

INVENTOR

Thomas J. Murphy,
by
Owen, Owen & Cawston.

UNITED STATES PATENT OFFICE.

THOMAS J. MURPHY, OF ROCHESTER, NEW YORK, ASSIGNOR OF ONE-HALF TO JAMES P. B. DUFFY, OF ROCHESTER, NEW YORK.

SOUNDER.

1,271,514.

Specification of Letters Patent.

Patented July 2, 1918.

Application filed October 2, 1916. Serial No. 123,420.

To all whom it may concern:

Be it known that I, THOMAS J. MURPHY, a subject of the King of Great Britain, and a resident of Rochester, in the county of 5 Monroe and State of New York, have invented a certain new and useful Sounder; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 My invention relates to telegraph sounders and it particularly has for its object to produce a sounding means which may be telegraphically operated by an alternating current. It particularly has for its object 20 to provide a sounding means which will produce a clear and distinct sound and will not chatter, due to the rebound of the sounding element.

Constructions containing the invention 25 may partake of different forms. I have shown in the drawing a construction containing the invention, it being understood that elements of the construction may be substituted by equivalent members, and yet 30 such altered constructions will contain the invention.

The construction selected for purposes of 35 illustration is shown in the drawings, wherein—

Figure 1 illustrates a sectional view of the sounder. Fig. 2 illustrates an end view and Fig. 3 illustrates a top view of the sounder, and also, diagrammatically, a system with 40 which the sounder may be connected.

1, Fig. 1, is a base for supporting the sounder, having binding posts 2, 3 and 4 for connecting the sounder with an external circuit. A container or housing 5 may be located on the base 1 which will operate as a 45 sounding box or element and which may also contain the alternating current electromagnets 6 having laminated cores 7.

On the top of the housing or container 5 is located a sounding element or lever 8 formed 50 of non-magnetic material and preferably of aluminum. The sounding element or lever

is supported centrally between two adjustable bearing screws 9 located in the yoke 10 which is secured to the top of the container 5. Armatures 19 are secured to the lever or 55 sounding element 8. They are disposed above the poles 7 of the magnets 6. A strip 18 of magnetic material extends along the sounding element or lever 8 and is secured to the top thereof. Intermediate the yoke 10 and the top of the movable sounding element or lever 8 is located the spring 26 which operates to hold the sounding element against the points of the screws 9 to prevent any loose play that might exist by 60 reason of wear or inaccurate adjustment of the screws.

A U-member or bracket 11 is located over one end of the sounding element or lever 8 which is secured to the top of the container 70 5. The yoke 10 is provided with a pair of upwardly extending arms 27. Brackets 14 and a permanent magnet are secured to the arms 27 by means of the screws 28. One of the brackets 14 extends over the U-member 75 11. Steel adjusting screws 12 are threaded into steel brackets 14. One screw 12 extends through the top of the U-member 11. The adjusting screws 12 are secured in their adjusted positions by knurled nuts 13. 80 The screws 12 and the brackets 14 being formed of steel or magnetic material, they operate to extend the field of the magnet 15 so that the steel screws 12 are permanently magnetized by the permanent magnet 15. 85 The bar 18 being formed of a magnetic material and extending from beneath one screw 12 to the other screw 12, the permeability of the field of the permanent magnet 15 is increased thereby.

90 The ends of the lever or sounding member 8 and the magnetic strip 18 are provided with steel screws 16 having flattened heads 17 which strike against the steel screws 12 when the lever or sounding member 8 is tilted one way or 95 the other. The lever or sounding member 8 thus completes the magnetic circuit of the permanent magnet 15, except for a short distance, at one or the other of the steel pins 12, when one or the other of the electromagnets 6 have separated one of the 100 ends of the sounding member 8 from the

steel pin located in proximity thereto. When one of the magnets 6 separates the sounding member 8 from one of the steel pins 12 it overcomes the sticking effect caused by the attraction between the steel pins 12 and 16. The opposite end of the sounding member 8 will be raised and the steel pins 12 and 16 of that end of the sounding member will come in contact with each other and the sounding member will be held against any rebound or chattering that might otherwise be produced; and the sound produced will be a clear, definite stroke, notwithstanding the fact that the sounding member 8 may be balanced centrally to permit equal action when either of its ends are drawn down by one or the other of the magnets 6.

The U-member 11 being located over but one end of the sounding element or lever 8, a different tone is produced when the lever strikes the other screw 12, which clearly indicates to the operator the beginning and the completion of the elemental part of the Morse signal which is transmitted over the line.

The sounder may be used in connection with one of a number of systems. I have shown in the drawing merely a conventional arrangement for the operation of the sounder. In Fig. 3 of the drawings, 20 is a source of alternating current, which is connected to the magnets 6 by means of the wire 21. The return is through either one of the branches 22 which are also connected to the magnets 6. A relay or key, directly connected, may be used for operating the sounder. I have shown in the drawing a key having a laterally operated lever 23 which is connected to the source of current 20 and which may connect the source 20 through either of the branches 22 by shifting either to the right or to the left, in which case one or the other of the magnets 6 would be operated, which will pull down one or the other sides or arms of the sounding member 8 to cause the opposite member to rise and strike against the steel pin 12, which will hold the balanced sounding member 8 to prevent any recoil or rebound. Suitable inductance may be inserted in the line 21 if desired. An adjustable induction coil 24 is shown in the system.

The current flows from the source of current 20 to the key 23, thence to one or the other of the contacts of the key, one or the other of the lines 22 and one or the other of the electromagnets 7. The current flows from one or the other of the magnets 7 according to which way the lever of the key is placed through the line 21 the adjustable induction coil 24 to the source 20.

I claim:

1. In a sounder, the combination of a pair of electromagnets, a balanced sounding member pivotally supported above the poles

of the electromagnets, a permanent magnet supported above the sounding member, the poles of the magnets and the ends of the sounding member having abutting steel screws, a member connected to one of the steel screws for producing a sound different from that when the other of the steel screws is struck by the sounding member.

2. In a telegraph sounder the combination of a movable sound producing member, electromagnets operating on the ends of the sound producing member, a source of alternating current connected to the electromagnet for operating the sounding member, a magnetic means for holding the sounding member to prevent chattering at the end of each movement of the sounder member. 75

3. In a sounder the combination of a pair of electromagnets, a pivotally supported sounding member operated by the electromagnets, a source of alternating current connected to the electromagnets for moving the sounding member, a permanent magnet, the poles of the permanent magnet terminating near the ends of the sounding member to 85 magnetically yieldingly retain the sounding member against movement produced by the electromagnets.

4. In a sounder the combination of a pair of electromagnets; a balanced sounding member pivotally supported above the poles of the electromagnets, a source of alternating current connected to the electromagnets for moving the sounding member, a permanent magnet, the poles of the permanent magnet and ends of the sounding member having abutting steel screws for yieldingly holding the sounding member. 95

5. In a sounder the combination of a pivotally supported sounding member, electromagnets for operating on the sounding member, a permanent magnet having abutting members for limiting the movement of the sounding member for yieldingly holding the sounding member, a resonant body connected to one of the abutting members for producing a sound different from that when the other abutting member is struck by the sounding member. 105

6. In a sounder the combination of electromagnets; a pivotally supported sounding member formed of diamagnetic material and having armatures operated upon by the electromagnets, a permanent magnet, the sounding member having a strip of magnetic material located below the poles of the permanent member for increasing the magnetizing effect of the permanent magnet. 110

7. In a sounder the combination of electromagnets, a pivotally supported sounding member formed of aluminum and having armatures operated upon by the electromagnets, a permanent magnet, the sounding member having a strip extending across the poles of the permanent magnet for increas- 125

ing the magnetizing effect of the permanent magnet.

8. In an alternating current telegraph sounder, a pivoted sounding member, electromagnets having laminated cores operating on each end of the sounding member, a

source of alternating current for alternately

energizing the electromagnets, and means for yieldingly holding the pivoted member against the attraction of the alternately energized magnets.

In testimony whereof, I have hereunto signed my name to this specification.

THOMAS J. MURPHY.
